216,362

DISPENSING BOTTLE FOR CHEMICAL REAGENTS OR THE LIKE

Robert E. McIlroy, Easton, Pa., assignor to J. T. Baker
Chemical Company, Phillipsburg, N.J., a corporation
of New Jersey

Filed Jan. 9, 1969, Ser. No. 15,264

Term of patent 14 years

Int. Cl. D9—01

U.S. Cl. D9—131

FIG. 1

FIG. 2

FIG. 3

FIGURE 1 is an elevational view of a dispensing bottle for chemical reagents or the like, embodying my new design;

FIGURE 2 is an enlarged fragmentary view of the upper portion with the cap removed; and

FIGURE 3 is an enlarged fragmentary view of the upper portion with the cap in place and the upper tip of the bottle broken off.

The bottle is circular in all horizontal cross-sections.
I claim:

The ornamental design for a dispensing bottle for chemical reagents or the like, as shown and described.
